UNITED STATES PATENT OFFICE

136,220

DESIGN FOR AN AUTOMOBILE ORNAMENT

Joseph B. Goodie, Towson, Md.

Application June 29, 1943, Serial No. 110,560

Term of patent 7 years

To all whom it may concern:

Be it known that I, Joseph B. Goodie, a citizen of the United States, residing at Towson, in the county of Baltimore and State of Maryland, have invented a new, original, and ornamental Design for an Automobile Ornament, of which the following is a specification, reference being had to the accompanying drawing, forming part thereof.

I claim:

The ornamental design for an automobile ornament, as shown.

JOSEPH B. GOODIE
